United States Patent Office.

JOHN YOUNG, OF AMSTERDAM, NEW YORK.

Letters Patent No. 64,180, dated April 23, 1867.

IMPROVED CLOTHES-WRINGER.

The Schedule referred to in these Letters Patent and making part of the same.

TO ALL WHOM IT MAY CONCERN:

Be it known that I, JOHN YOUNG, of Amsterdam, in the county of Montgomery, and State of New York, have invented a certain new and useful improvement in Clothes-Wringers; and I do hereby declare that the following is a full, clear, and exact description of the construction and operation of the same, reference being had to the annexed drawings, making a part of this specification, in which—

Figure 1 is a longitudinal central section of a portion of a clothes-wringer, showing the position of the upper gear.

Figure 2 is an axial view of my compromising gear.

The object of this invention is to admit of the upper roller or rollers of clothes-wringers to rise and fall, (as is well known they must,) with relation to the lower driving one, by giving a peculiar form to the gear applied to the upper roller and its points of bearing, in order that the pitch-circles of both upper and lower gears shall be in practical harmony with each other.

A, fig. 1, represents the uprights of a clothes-wringer, B the upper, and B' the lower or driving-shaft. Said roller-shaft B' has a gear, c, secured thereto by means of a pin, as shown, in the usual way. The upper shaft B has a pin, d, driven therein near its outer end, which serves as a "driver" to said shaft by being fitted into the recesses e of the gear F. The gear F has also conical depressions formed in its hub, as shown, the outer one of which turns on a conical pivot or stud, g, secured to a suitable standard or bracket, h, and the inner depression is made to loosely fit the rounded end of the shaft B in such a manner that the said shaft may be easily elevated as far above as is now represented below a level of the stud or conical bearing or centre, g, without "binding." It will be seen that the gear F performs a sort of gyratory motion when the clothes are being passed through between the rollers. The bracket h is formed with an appropriate depression and swell, as shown in fig. 1, in order that the whole may be very neat and compact.

Having thus described my invention, what I desire to secure by Letters Patent, is—

1. I claim the gear F, when applied to the upper shaft B of clothes-wringers, in the manner herein shown and described, and operating as set forth.

2. I claim, in combination with the gear F, the cone or centre g, and pin d, arranged as described, when used in connection with the gear c, as specified.

JOHN YOUNG.
